United States Patent Office

Des. 228,953

Patented Oct. 30, 1973

228,953

PORTABLE RADIO CABINET

Melvin H. Boldt, Glenview, and Francis J. Greb, Chicago,
Ill., assignors to Zenith Radio Corporation, Chicago, Ill.

Filed Jan. 19, 1972, Ser. No. 219,205

Term of patent 3½ years

Int. Cl. D14—03

U.S. Cl. D56—4 B

FIG. 2

FIG. 1

FIG. 3

FIG. 4

FIG. 5

FIG. 6

FIG. 1 is a front elevational view of a portable radio cabinet, showing my new design;

FIG. 2 is a left side elevational view;

FIG. 3 is a right side elevational view;

FIG. 4 is a top plan view;

FIG. 5 is a bottom plan view; and

FIG. 6 is a rear elevational view thereof.

Portions of the drawing figures are shaded to indicate contrast in appearance.

We claim:

The ornamental design for a portable radio cabinet, substantially as shown and described.
